UNITED STATES PATENT OFFICE.

HOMER H. TRAVIS, OF COLUMBUS, OHIO.

HEADLIGHT.

1,270,672.

Specification of Letters Patent. Patented June 25, 1918.

Application filed December 22, 1916. Serial No. 138,301.

To all whom it may concern:

Be it known that I, HOMER H. TRAVIS, a citizen of the United States, residing at Columbus, in the county of Franklin and State of Ohio, have invented certain new and useful Improvements in Headlights, of which the following is a specification.

The present invention relates to improvements in headlight attachments and it is the 10 principal object of the invention to provide an attachment whereby the light rays emitted by the headlight may be dimmed when an intense light is not required, such as upon the streets of a city or other illuminated 15 highway.

The preferred embodiment of my invention is shown in the accompanying sheet of drawings, in which similar characters of reference designate corresponding parts, and 20 in which:

Figure 1 is a view of a lamp constructed in accordance with my invention, the rear portion of this lamp being shown in vertical section and also showing the electric bulb 25 in its forward position, wherein an intense beam of light is produced.

Fig. 2 is a similar view of the rear portion of the reflector, but showing the electric bulb in its rearmost position to produce 30 a non-glaring light, and.

Fig. 3 is a section taken on line 2—3 of Fig. 1.

In these drawings, the lamp casing or body is designated by the reference numeral 1 and within this casing, there is located the usual type of reflector 2. This reflector may be mounted within the casing in any desired manner, this portion forming no part of the present invention. The reflector is, however, provided with a central opening 3 in its rear which is large enough to permit the free passage rearwardly therethrough of the electric bulb 4. Within this opening 3, there is rigidly secured a sleeve 5, within 45 which a slide member 6 is slidably mounted. This slide member is also provided with a central sleeve 7, within which the socket member 8 for the lamp is adjustably secured, by means of the adjusting screw shown at 9. 50 The socket member 8 and lamp 4 are of the type now generally in use and the adjustment to obtain the proper focal position of the lamp, may be effected by loosening the screw 9 and moving the socket member to 55 its desired position, afterward tightening

the screw 7 to rigidly maintain this position. The electrical connections to the bulb are of the conventional form and current may be supplied thereto through the medium of wires 10. It will be noted by reference to Figs. 1 and 2 that the sleeve 5 is of a size 60 to permit the movement thereinto of the bulb 4 and in order that this may be accomplished from the driver's seat, I have slotted the sleeve as is shown at 11. The slide 65 member itself is provided with an upwardly projecting ear 12 operating in this slot to effect the adjustment of the bulb and to also prevent the relative rotation between the sleeve and slide member. To this ear there 70 is connected a wire 13 which passes out through the casing, as shown at 14 and is confined within the flexible tubing 15. This tubing and wire may lead to any position, but preferably to a position adjacent the 75 driver's seat.

Thus, when an intense beam of light is desired, the electric bulb is moved to the position shown in Fig. 1. If this bulb is not in proper focal alignment with the reflector, 80 the lens ring 16 is removed and the reflector withdrawn temporarily, to permit the adjustment back or forth of the bulb 4, by first loosening the screw 9 which may be effected through the openings 17 and 18 in 85 the sleeve 5 and slide member 6 respectively. After the proper adjustment has been attained with the ear 12 at its forward limit of movement, as is shown, the screw is again tightened and the lamp assembled. 90 Should it then be desired to have a non-glaring light, the wire 13 may be withdrawn so that the bulb 4 is moved to a position within the sleeve 5, as is shown in Fig. 2. The same rays of light are given off by the 95 lamp in this position, but these rays are not concentrated by the reflector 2. The light given in this position has been found to be amply sufficient for all city purposes and the glare from the reflector is thereby removed. When it is desired to again move the lamp to its forward position, the proper focal position thereof will be found to be at that point where the ear 12 engages the edge 100 of the reflector 2, as is shown in Fig. 1. 105

What I claim, is:

In combination with a reflector having an opening formed in the rear portion thereof, a sleeve engaged in said opening provided with a longitudinally extending way and an 110

2
opening, a tubular member slidable in said sleeve and having an opening formed therein adapted to align with said opening in the sleeve, a lug carried by said member received in the longitudinal way, a second sleeve carried by the tubular member for receiving an electric lamp therein, and lamp engaging means on said second sleeve posi-

tioned adjacent the opening formed in the 10
slidable member.

In testimony whereof I affix my signature
in presence of two witnesses.

HOMER H. TRAVIS.
